CREAM REMOVER

Gerhard Severud, Oslo, Norway

Application April 25, 1949, Serial No. 89,414
In Norway November 9, 1948

8 Claims. (Cl. 210—51.5)

1

This invention relates to an apparatus for taking out cream from milk containers. It consists of a small container of rigid or semi-rigid material with upwardly directed walls, open above and in the bottom, a valve adapted to close the bottom opening of the small container and bars or other means so connected with the container or the valve that the container may be manipulated and the valve opened and closed from a place located outside the container. Preferably the apparatus consists of a cylinder with bottom valve. The invention aims particularly at executing an apparatus of this kind in such a way that the manufacture is simple and reliable, while at the same time the operation is satisfactory. Particular stress has been laid on producing the individual parts of the apparatus by stamping out from metal sheets. It seems then most convenient according to the invention to hinge the bottom valve on the lower edge of the cylinder instead of having it fixed directly to a bar which can be moved up and down. Preferably the bottom valve is provided with an inclined projection which turns to the side in such a way that it can be swung together with the valve proper by the end of a needle which slides along the cylinder at its outer end. The said projection is provided with two protruding, horizontal pivots which get their bearing in lugs on the lower edge of the cylinder. The cylinder is split longitudinally and the split edges are bent outwards and backwards through about 180°. The needle which serves to open or close the valve is guided by a guide forming a channel which has an approximately circular, but open, section, and may be thread upon the split edges of the cylinder in such a way that it grips round same so as to close the cylinder along the split.

One embodiment is illustrated in the drawing, in which Fig. 1 shows a vertical section through the apparatus. Fig. 2 shows a cross section on the line 2—2 in Fig. 1, Fig. 3 an elevation of the cylinder itself in unmounted state, Fig. 4 is a cross section on the line 4—4 in Fig. 1, and Fig. 5 is a plan view of the bottom valve alone.

The cylinder is bent from a uniformly thick metal sheet, conveniently of brass, so that it assumes a cylindrical shape, split longitudinally at 2 (see Fig. 3). In this condition, the cylinder is somewhat larger than it will be when the various parts of the apparatus are assembled. The split edges of this cylinder are bent back approximately through 180°, as shown at 3 in Figs. 3 and 4, and corresponding thereto a guide 4 is used for the needle on rod 5, which operates the valve. This guide 4 is also bent together from a relatively long metal strip into an approximately cylindrical channel, as will be seen from Figs. 2 and 4. The longitudinal edges do not quite meet, and the distance between them is so

2

arranged that the guide can be slid or slipped upon the two cylinder edges 3 when these are pressed together, so that the split 2 is closed. In this state the guide can be slid down along the sides of the cylinder and will consequently close the cylinder at the split 2, whereby the parts assume the mutual position shown in Fig. 4. The guide furthermore has a pair of members 6 and 7, of which 6 is open at the side, while 7 is perforated for the penetration of the needle 5. The latter is passed by the cylinder 4 and projects at 5' below the bottom of the cylinder, where it is adapted to act on a tongue 8 projecting from the bottom valve 9. This is also stamped out from sheet metal and is circular in shape so as to fit against the lower edge of the cylinder 4 closed toward the guide 4.

This cylinder is at the bottom provided with two bearing lugs 10 for projecting pivots 11 on the bottom valve 9. These bearing lugs are in the unattached state of the cylinder 4 at such a distance from each other that it is possible without difficulty to push the pivots 11 into position. But when the cylinder 4 is closed by pushing down the guide 4, the bearing lugs 10 will be moved so closely together that they will engage approximately the side edges of the projection 8 and thereby lock the hinge connection between the bottom valve 9 and the cylinder 4 so as to prevent removal of the valve. This position of the bottom valve will be seen in Fig. 1 where the projection 8 has an inclined position downwards relatively to the horizontal bottom valve 9. In the position shown in Fig. 1, the end 5' of the needle presses against the projection 8 and thereby keeps the bottom valve 9 closed. If on the other hand the end 5' of the needle is drawn up a little in its guide by means of the ring handle at the top, the needle end 5' will release the projection 8, whereby the bottom valve 9 will swing down into a vertical position by its own weight. In this condition the apparatus can be inserted into the top of a milk bottle to a suitable depth, so that the top portion of cream enters into the cylinder 4. Then the needle 5 is pushed down by means of the handle, so that the valve is closed, whereupon the apparatus is lifted out with the cream.

The various parts of the apparatus may also be produced of other materials than metal, viz. plastic, press material etc.

For sanitary purposes the apparatus is so designed that the individual parts can easily be taken apart for cleaning. For the same reason the use of closed pipes is avoided, which would have had to be soldered or welded to the apparatus, whereby rests of milk or cream might easily pass up into the closed parts and get contaminated if an effective cleansing were difficult or impossible.

I claim:

1. In a cream remover adapted to be inserted into a milk bottle, the combination of a sheet material member forming a split cylinder with the longitudinal edge portions adjacent said split bent outwardly away from each other, said cylinder being open at its top and bottom and having ears at the bottom end thereof, a closing member detachably and frictionally engaging said longitudinal edge portions so as to bridge said split and substantially close the same, a bottom member having lateral extensions detachably engaging said ears so as to hinge said bottom member to said cylinder, said bottom member being operable selectively to close or open the bottom of said cylinder, and rod means movably arranged adjacent said closing member and operable selectively to close said bottom member.

2. In a cream remover adapted to be inserted into a milk bottle, the combination of a cylinder open at its top and bottom and provided with a longitudinal split, the longitudinally extending edges of said cylinder adjacent said split being bent outwardly and away from each other, the bottom end of said cylinder being provided with ears, a sliding member detachably and frictionally embracing said outwardly bent edges so as to bridge said split and substantially close the same, a bottom member detachably hinged to said ears and operable selectively to close or open the bottom portion of said cylinder, and rod means extending through said sliding member and operable selectively to open said bottom member.

3. In a cream remover adapted to be inserted into a milk bottle, the combination of a cylinder provided with a longitudinal split, the ends of said cylinder confining said split being bent outwardly so as to form a track, a sliding member slidably and frictionally engaging said track to bridge said split and substantially close the same, said cylinder being open at its top and bottom and having ears connected to the bottom portion of said cylinder, a closure member having lateral extensions extending into said ears for hinging said closure member to said cylinder, said closure member being hinged so as to continuously tend to open by its own weight, and rod means movably arranged adjacent said sliding member and operable to engage a portion of said closure member for selectively holding said closure member in closed position.

4. In a cream remover adapted to be inserted into a milk container, the combination of a cylindrical member open at the top and bottom and provided with a longitudinal split extending from the top to the bottom of said cylindrical member, the material of said cylindrical member being sufficiently elastic to allow a slight compression of said cylindrical member to reduce the distance between the adjacent edge portions defining said split, said edge portions being bent outwardly away from each other, a closure member detachably and frictionally gripping behind said outwardly bent edge portions, closing means hinged to the bottom portion of said cylinder, and rod means movably arranged adjacent said closing member and operable to engage said closing means for selectively closing the same.

5. A cream remover comprising in combination, a longitudinally split sheet metal cylinder

open at the top and bottom and adapted to be inserted into the neck of a bottle, a valve plate, hinge means associated with said valve plate and pivotally connecting said valve plate to the bottom portion of said cylinder, said valve plate being arranged so as to tend continuously to open under its own weight and being provided with a tongue protruding from said valve plate beyond the hinge means for said valve plate, means detachably connected to said cylinder and substantially closing the split in said cylinder, and actuating means slidably mounted in said last mentioned means and operable selectively to engage said tongue of said valve plate.

6. A cream remover comprising in combination, a sheet metal cylinder being longitudinally split and having the edge portions adjacent said split bent outwardly and away from each other by approximately 180°, a sheet metal guide having approximately circular cross section but being open so as to allow slipping of said guide upon said outwardly bent edge portions, a valve plate hinged to the bottom portion of said cylinder and arranged so as continuously tending to move into its open position by its own weight, said valve plate being provided with an extension protruding beyond the hinges of said valve plate, and rod means slidably mounted in said guide and movable so as selectively to engage said extension for moving said valve plate into its closing position.

7. A cream remover comprising in combination, a longitudinally split cylinder of sheet material having the edge portions adjacent said split bent outwardly away from each other through approximately 180°, said cylinder having an opening at the top and the bottom, a guiding member slidably and frictionally gripping around said bent edge portions and substantially closing said split, bearing means adjacent the bottom portion of said cylinder, a valve plate provided with tongue means and also with pivot means engaging said bearing means to hinge said valve plate to said cylinder, said tongue means forming an angle with the plane of said valve plate and in close position of said valve plate extending away from the bottom portion of said cylinder, and rod means operable selectively to be moved away from said tongue means or to engage said tongue means for causing said valve plate to open.

8. A cream remover according to claim 7, characterized in that said pivot means extend in opposite directions from said tongue means and form an integral unit with said tongue means and said valve plate.
